M. BUCH.

FOLDING TOP FOR VEHICLES.
APPLICATION FILED MAY 27, 1918

1,287,629.

Patented Dec. 17, 1918.

Inventor:

Max Beck,

by Stan Middleton Donaldson Stan
Atty's.

UNITED STATES PATENT OFFICE.

MAX BUCH, OF DETROIT, MICHIGAN, ASSIGNOR TO HENRY E. EDWARDS, OF JACKSON, MICHIGAN.

FOLDING TOP FOR VEHICLES.

1,287,629.

Specification of Letters Patent. Patented Dec. 17, 1918.

Application filed May 27, 1918. Serial No. 236,891.

To all whom it may concern:

Be it known that I, MAX BUCH, a subject of the Emperor of Germany, residing at Detroit, Michigan, have invented certain new and useful Improvements in Folding Tops for Vehicles, of which the following is a specification.

My present invention relates to folding tops for vehicles and the like of what is known as the one man type.

One object of the invention is to provide a construction in which the parts projecting forwardly from the main bow or standard shall be self-balanced in the folding and unfolding movement.

Another object is to so arrange the linkage of the top as to remove all danger of the pinching of the fingers of the operator and to reduce the liability of injury to the fabric covering.

The invention further aims to provide a construction which shall be specially adapted for short bodied cars of the roadster type.

With these and other objects in view the invention includes the novel features of construction and arrangement and combination of parts hereinafter described and particularly defined by the appended claims, an embodiment of the invention being illustrated in the accompanying drawing in which,

Figure 1 is a side elevation of the top as applied to an automobile body.

Fig. 2 is a detail view of a modification.

In this drawing the top being shown in side elevation, only the main bow or standard, bow arms and linkage on one side appear, but it will be understood that they are duplicated on the other side, only one side being shown for convenience.

Similarly in the following description and claims reference is made, for convenience, to the members on one side only.

In the drawing and referring first to Fig. 1, the numeral 1 designates the body of the vehicle for which the top is adapted, and which is intended to be representative of any type of vehicle or motor boat needing such a protective covering. The top covering material is indicated at 2, supported by the following described folding frame. This comprises a main standard 3, which, as applied to a short body of the roadster type, inclines rearwardly as shown and carries a bow W which may be made of an integral

part of the main standard, to provide an all steel construction, or may be in the form of a wooden bow secured to the standard in the usual or any approved manner.

The lower end of the standard is pivotally connected with the body at 3^a.

5 designates the outrigger bow arm carrying the bow W' which may likewise be made an integral part, or an attached wooden bow. The rear end of the outrigger bow arm 5 is pivotally connected at 5^a with the front end of a link 9, the rear end of which is in turn pivotally connected to the main standard 3 as indicated at 9^b.

A cover supporting bow arm 7 is pivotally connected to the outrigger bow arm 5, and the bow W² thereof may be integral or attached as desired. A link 8 is pivotally connected to the cover supporting bow arm 7 at a suitable point indicated at 8^a and this link has an angular portion 8^c which is connected both to the link 9 and to the front end of a link 6 which is spaced from link 9 and has its rear end pivotally connected to the standard 3 above the pivot 9^b.

The link 8 and its angular portion in effect constitute a bell crank lever having its long arm connected to the bow 7 and one part of its short arm fulcrumed to the link 8 at 9^c while another part of the short arm is pivoted to the forward extremity of link 6 as indicated at 8^b.

In the form shown in Fig. 1 the short arm is turned downwardly and its extremity is fulcrumed at 9^c to link 9 the pivot 8^b being located at the bend or angle of the bell crank. In the form shown in Fig. 2 the position of the short arm of the bell crank lever is reversed.

To provide a stop to limit the upward movement of the parts in the form shown in Fig. 1 I preferably curve the adjacent end portions of outrigger bow arm 5 and link 9 upwardly so that the pivot pin 5^a or a projection thereon will make contact with the underside of link or arm 8.

In the form shown in Fig. 2 the outrigger bow arm 5 is provided with a stop pin 10 which serves the same purpose.

Having thus described my invention, what I claim is:

1. In a folding top, a main standard, an outrigger bow arm, a link connecting the outrigger bow arm with the main standard, a cover supporting bow arm pivoted to said outrigger bow arm, a bell crank lever ful-

- crummed on said link and having a long arm pivotally connected to said cover supporting bow arm, and a second link connecting said bell crank lever with said main standard.
- 5 2. In a folding top, a main standard, an outrigger bow arm, a link connecting the outrigger bow arm with the main standard, a cover supporting bow arm pivotally connected with said outrigger bow arm, a link 10 pivotally connected with said cover supporting bow arm and having an angularly turned portion at its rear end, one part of said angularly turned portion being pivoted to said first named link, and a third link 15 connecting another part of said angularly turned portion with the standard above the point of connection of the first named link.
3. In a folding top, a main standard, an outrigger bow arm, a link pivotally connecting the outrigger bow arm to the standard, a cover supporting bow arm pivoted to the 20 outrigger bow arm and inclining normally rearwardly in relation thereto, a second link substantially parallel to said first named link and pivotally connected with the standard at its rear end and a third link pivotally connected respectively with said first named link and with said cover supporting bow arm, said third link having an offset or extension pivotally connected with said second link. 25
4. In a folding top, a rearwardly inclined main standard, an outrigger bow arm, a link pivotally connected with said standard and outrigger bow arm, a cover supporting bow 30 arm pivotally connected with said outrigger bow arm and inclining rearwardly relative thereto, a link connected with the cover supporting bow arm and having an angular portion pivotally connected with said first 35 named link, and a third link substantially parallel with said first named link and connecting said angular portion with said main standard. 40

In testimony whereof I affix my signature. 46
MAX BUCHI.
